UNITED STATES PATENT OFFICE

129,102

DESIGN FOR A MOTORCYCLE FENDER GUARD

Charles A. Comiskey, Chicago, Ill.

Application May 22, 1941, Serial No. 101,081

Term of patent 14 years

To all whom it may concern:

Be it known that I, Charles A. Comiskey, a citizen of the United States and resident of Chicago, in the county of Cook and State of Illinois, have invented a new, original, and ornamental Design for a Motorcycle Fender Guard, of which the following is a specification, reference being had to the accompanying drawing, forming part thereof.

Fig. 1 is a perspective view of a motorcycle fender guard showing my new design;

Fig. 2 is a plan view; and

Fig. 3 is a side elevational view thereof.

I claim:

The ornamental design for a motorcycle fender guard, as shown.

CHARLES A. COMISKEY.
